UNITED STATES PATENT OFFICE

WILLIAM MOORE SCHWEICKART, OF RAMSEY, NEW JERSEY, ASSIGNOR TO AUTOMATIC COAL BURNER COMPANY, OF SEATTLE, WASHINGTON, A CORPORATION OF WASHINGTON

COAL CONVEYER

Application filed May 9, 1930. Serial No. 450,968.

The object of my invention is to provide a mechanical-type conveyer that is suitable for carrying coal from the coal bins to the furnaces and stokers in residences and apartment houses, and in other like situations; that is to say, in situations where (hand-firing, say, being contemplated at the time of the construction of the building) various relations between and relative placements of 5 the furnace or stoker on the one hand and the coal bin on the other are met with.

In the accompanying drawings, my invention is illustrated as applied to a stoker of household type. Figure 1 is an elevation of 10 a furnace, its stoker and the coal bin, with the conveyer applied thereto. Figure 2, partly in section, is a detail of the conveyer and one arrangement for supporting it. Figure 15 3 is a plan view substantially on the line 3-3 of Figure 1. Figure 4 is a detail of a modification.

In the drawings, a household furnace is shown at 1, the hopper of the automatic coal 20 stoker for the furnace is shown at 2, and at 25 3 is the bin containing the supply of coal for the furnace. It will be understood as the description proceeds that the invention is not limited to the relation of bin to stoker (or furnace) illustrated, but that the bin may 30 occupy almost any position around the stoker (or furnace) and may be nearer to it or farther away. The conveyer of the present invention is readily adapted to any such situation that may be encountered. Various 35 types of household stokers are known, and since the present invention is not concerned with the particular type of stoker (and indeed is applicable also to feed coal to a furnace direct, as before indicated) the stoker 40 illustrated need not be further described. A hopper with a flat top 4 has been chosen for 45 illustrative purposes, because of its simplicity; the invention is not limited to flat topped hoppers however, as also will become apparent.

The coal-conducting portion of the conveyer comprises two parts, a reach, as I call it, consisting of a tube or trough 5 (or simply a supporting or enclosing structure) together 50 with the coal-carrying mechanism associated

therewith, here a motor-driven screw 6, which reaches from the coal bin to the receiver, and a snout 7 at the furnace-end of the reach and into which the reach delivers and down which the coal runs by gravity into the receiver 55 (stoker, hopper, furnace, furnace magazine, or whatever the receiver may be). The bin-end of the reach, it will be understood, is placed wherever it may receive coal from the bin, either adjacent or within the bin. The 60 reach 5-6 is so connected to the receiver (hopper) 2 as to be capable of two adjustments; first, in the vertical plane, to different angles from the horizontal downwardly toward the vertical; second, to different positions radially from the vertical center line of the receiver 2. I fixed the snout 7 rigidly to the reach structure 5, and usually I fix the snout to the reach at a fairly large angle, for example, at right angles thereto or at an angle 70 approaching a right angle. Preferably therefore, I rigidly fix the snout 7 to the reach structure 5 at about a right angle thereto; hinge the snout 7, as shown at 8, in a direction at right angles to the reach, to a member 75 9 whereby the snout is connected to the support for this end of the conveyer (here represented by the receiver top 4); and so connect the snout member 9 to the support 4 that the snout is adjustable around the vertical 80 center line of the horizontal area at the top of the receiver through which the snout delivers. To provide for this latter adjustment, the member 9 or snout plate may be connected to the conveyer-support 4 by means of bolts 85 passing through arcuate slots 14 as shown in Figure 4 for example; preferably however the snout plate 9 has the form of a disc and is held in an annular clamp 15-16 as shown in Figure 2; the clamp member 15 is rigidly attached to the support 4 while the cooperating clamping ring 16 is tied to 15 by nuts and bolts 17. The snout 7 is then made of such length as to permit the reach 5 to pass the side of the receiver 2, regardless of how 95 nearly vertical it is likely to be necessary to place the reach. When the horizontal dimensions of the receiver 2 are not inconveniently large, the opening in its top 4 for the snout may be placed at, say, the center of the top, 100

and thence the reach led off at any necessary angle to the horizontal angle and in any direction. When the receiver is so large that this requires a longer snout than may be available or desirable, the snout opening may be placed near one side of the top, and the top (or other support) may be arranged for placement in various positions in the horizontal plane, so that the snout can be placed 5 in the most favorable position for holding the reach away from the receiver. For example, this is illustrated in the present instance by the arrangement of the snout to deliver into the receiver near one corner of 10 the latter; by removing the bolts 18 which hold the conveyer-support (top) 4 to the receiver, this support 4 can be re-set to place the snout at any one of the four corners of 15 the receiver.

20 Preferably the reach is a cylindrical tube 5 with a screw 6 for carrying the coal therethrough as before pointed out. When it has this construction, I prefer to use a tube having an internal diameter considerably larger 25 than the external diameter of the screw, for I have found that a screw bearing such a relation to the tube requires less power to operate than a screw having a diameter more nearly equal to the internal diameter of the 30 tube; I have found that an internal tube diameter of about three inches to a screw diameter of two inches is a good relation. The screw 6 may be, and preferably is, journaled at 22 in the snout wall; it need not be journaled elsewhere throughout its length. To 35 turn the screw, I preferably use an electric motor 23 and a worm-and-worm-gear speed reducing gearing 24 interposed between the motor shaft and the furnace-end of the screw, 40 the motor and speed reducing gearing being mounted on the snout 7. Other driving mechanisms for the screw may be substituted however.

The reach 5—6 being readily adjusted from 45 the horizontal well downwardly (by reason of the hinge 8), and being capable of taking almost or quite a vertical position without interference from the receiver (either because of the snout 7 alone or because of the 50 snout in co-operation with the passing of the snout into the receiver at one side of the vertical center line of the latter and the adjustability of the snout support around that center line) and likewise the reach being adjustable to substantially any position around the 55 vertical center line of the receiver, it is apparent that such a conveyer as I have described is suitable for the various relations of coal bin to furnace met with in residences 60 and apartment houses. In length, the reach will be cut to suit the particular situation encountered.

As indicated in Figure 2, the delivery end 65 of the snout may be bent so that it will substantially close the snout-opening in the

snout plate 9, regardless of the angle to the horizontal at which the snout may be placed.

It is obvious of course that the conveyer can be controlled (or even actuated) manually, or it may be started and stopped entirely automatically, as conditions may demand. As a safeguard, or as a control, when the conveyer is motor driven, I usually provide an automatic switch for opening the motor circuit when the free flow of coal from the snout is interfered with, thus assuring the conveyer being stopped when the receiver has been filled. To this end, an auxiliary opening for the escape of coal may be provided, say at or near the snout, and thereat a motor-controlling switch placed for operation by coal escaping or tending to escape from the auxiliary opening. For this purpose, the upper end of the snout 7 is closed by a flap or cover 26 hinged at 27, and on this is mounted a 85 switch in the form of a glass tube 28 penetrated at one end by two wires and containing a little mercury for bridging the two wires. Switches of this type are well known. The tube 28 may be carried by a bracket 29 which is adjustable for the purpose of permitting the tube 28 to be set at various angles. On the installation of a conveyer, the bracket 29 is so adjusted that when the flap 26 is closed against the end of the snout, the 90 mercury in the tube bridges the two wires, but when the flap is raised a little (by coal backing up in the snout and thence seeking to escape from beneath the flap) the mercury runs toward the opposite end of the tube and thus disconnects the two wires, one from the other. A switch so installed may be interconnected with the motor circuit in various ways, to the end that it will stop the motor when the flap is raised, as will be apparent. 105 For illustrative purposes I have shown the switch connected in series with the motor; from the incoming power or supply lines 31, one lead 32 goes direct to a motor terminal; a second lead 33 connects the other motor terminal to one of the two wires piercing the tube 28; and the third lead 34, containing the switch 35 by which the motor is started (and perhaps normally stopped), connects the other of the two wires piercing the glass tube 110 28 to the remaining side of the incoming lines 31.

It will be understood that my invention is not limited to the specific construction illustrated and described above, except as appears hereinafter in the claims.

Claims:

1. The combination of a coal receiver of the kind indicated, a coal conveyer for conveying coal from a coal bin to said receiver comprising a reach, a delivery snout fixed to the receiver end of the reach and delivering into the receiver, a snout plate and means hinging the snout to the snout plate on an axis extending substantially horizontally and 125

- transversely of the reach, and means permitting adjustment around a vertical line passing through the snout plate for supporting the snout plate on said receiver.
- 5 2. The combination with a coal receiver of the kind indicated and a coal bin, of a conveyer for conveying coal from the bin to said receiver comprising a reach, a snout fixed to the receiver end of the reach and a
 10 snout plate fixed at the receiver for supporting the snout and receiver-end of said reach, said snout-plate being hinged to the snout for adjustment of the reach in a vertical plane and the connection of the snout-plate at the
 15 receiver permitting adjustment around a vertical line passing through the snout-plate.
3. The subject matter of claim 1, characterized by the fact that the reach consists of a tube with a conveyer screw therein.
- 20 4. The subject matter of claim 1, characterized by the fact that the reach consists of a tube with a conveyer screw therein, and by the fact that a motor and speed-reducing mechanism to drive the conveyer screw is provided, said motor and speed-reducing mechanism being mounted on said snout.
5. The subject matter of claim 1, characterized by the fact that the snout is provided with an auxiliary opening for the escape of
 30 coal when free flow through the snout is interfered with, and means operable by the coal escaping through said auxiliary opening is provided thereat.
6. A coal conveyer of the kind indicated
 35 comprising a tube, a conveyer screw therein, a snout fixed to the delivery end of the tube, hinge means at the delivery end of the snout for adjustment of the tube in a vertical plane, an electric motor, speed-reducing gearing connecting the shaft of said motor to said screw, said motor and speed-reducing gearing being mounted on said snout, a hinged flap closing the end of the snout adjacent the point of delivery of said tube
 40 thereto, and a switch connected to said flap for operation thereby.
- 45 In testimony whereof, I have signed this specification.

WILLIAM MOORE SCHWEICKART.
